GRATE STRUCTURE FOR REFUSE BURNING FURNACES

Henry C. L. Miller, Richmond, Va., assignor to The Hoff Company, Inc., a corporation of Indiana

Original application December 29, 1948, Serial No. 67,802. Divided and this application October 19, 1949, Serial No. 122,168

1 Claim. (Cl. 110—8)

This application is a division of application Serial No. 67,802, filed December 29, 1948, for Refuse Burning Furnace (now abandoned), and relates to improvements in furnaces of the type adapted for burning such fuels as bark, cotton seed, cocoanut hulls, sewer sludge, garbage, and like material having a high moisture content, and wherein such material often embodies such non-combustible foreign matter as dirt, sand, and the like. Such furnaces are utilized both for consuming said material and utilizing the heat produced for boiler or other power producing purposes, reference being had as illustrative of the art to Letters Patent to Hoff et al. No. 2,257,957, issued October 7, 1941, for Furnace Grate and to Puckett No. 2,381,182, issued August 7, 1945, for Apparatus for Burning Refuse.

It is the object of the present invention to develop improvements in the grate structure of furnaces of this character which will overcome various problems of combustion and control in the burning of moisture and sand-laden materials.

The feature of this invention resides in the zoned air control of the grates. In furnaces of this type the upper section upon which the fuel is first received is generally imperforate, merely providing a forehearth for receiving the fuel and directing it on to the grate bars. For the purpose of facilitating the drying action and burning of wet fuel, the forehearth is provided with a plurality of small apertures forming a pinhole grate, and is in communication with a damper controlled air duct communicating with the air chamber below the grates. However, in respect to the dump area over which intense combustion takes place, a separate air zone is provided which is damper controlled for individually regulating the combustion in the dump area in comparison with the entire grate area. Thus, zoned air control is provided, the primary zone being in communication with the grate surface between the forehearth and the dump, a controlled zone of air supply being provided for the forehearth and a controlled zone of air supply being provided for the dump area. In this manner the fuel is more efficiently conditioned in passing over the forehearth on to the grates and the combustion thereof is better controlled as between the grate and dump areas.

Other features of the invention will become apparent from the following description and claims of the invention as more particularly set forth herein.

Fig. 1 is a central vertical section through the furnace.

Fig. 2 is a view of the grate cleaning blowers taken substantially on the line 2—2 of Fig. 1.

Fig. 3 is an elevational view of the dump area of the furnace taken substantially on the line 3—3 of Fig. 1.

Fig. 4 is a section through the dump and adjacent grate elements.

Fig. 5 is an elevational view of the pivotal mounting of the dump with portions broken away.

In the drawings there is shown a furnace for the burning of wet fuels which are fed therein through the intake duct 10, generally from a superimposed hopper. The fuel indicated at 11 passes on to a solid forehearth section 12. The forehearth includes an air zone section for predrying of the fuel which comprises a perforated or pinhole grate 13. The forehearth sections are supported at the rear by a frame including vertical legs 14 and the cross beam 15. The forward end of the forehearth is carried by the wall 16 of the

furnace. The grate section of the furnace includes a series of grate bars 17 carried by the I-beams 18 intermediate a series of parallel spaced water cooled tubes 19. The fuel supporting surface of the grate, therefore, comprises the water cooled tubes with the interposed grate bars 17. Said grate bars have substantially horizontally extending fuel supporting surfaces mounted in spaced relation to provide air passages of the usual stelpladder type.

Below the grate bars there is provided a tuyère section having a series of pivotally mounted pusher fingers 20 interposed between the tubes 19, which continue downwardly terminating in a transverse header tube 21. Said header tube is provided at each end with a return flow pipe 22, being supported by a transverse bearing cradle 23 mounted on the cross beam 24 carried by the side walls 25 of the furnace.

Mounted transversely of the furnace adjacent the header tube 21 there is provided a pivotally mounted dump consisting of a series of dump bars 26, which span the ashpit 27. Each dump bar is formed at one end thereof with a counterweight 26a extending adjacent the header tube 21. The under surface of the grate bars adjacent the counterweight 26a is formed with an arcuate bearing portion 28 and a slotted recess 29. The bearing portion 28 of each dump bar has its bearing upon the water cooled pivot tube 30. Said tube is formed along one side thereof with a lug 31 engageable within the slotted keyway 29. Said tube, which provides a water cooled pivot for the dump, carries a water inlet pipe 32 extending therethrough, but terminating short of one end thereof.

At the opposite end there is a water outlet 33, the arrangement being such that cooling water is discharged into the pivot tube at one end and passes therethrough and out the same end. The counterweight 26a has its rear surface arcuately formed with its center of curvature on the axial center of the pivot tube 30. It extends adjacent the header tube 21 and through such an arc as to at all times extend in substantial sealing relationship with the header tube when the dump is lowered with the dump bars extending vertically downward, as shown in dotted lines. Thus, the counterweight serves to hold the fuel bed when the dump is lowered and thereby prevents unburned fuel from sliding down into the ashpit during the dumping operation.

The upper edge of the counterweight is formed with a rearwardly extending and curved knob 34 having a reverse curvature substantially conforming to the curvature of the tube 21 providing a bridge for the fuel passing from the grates on to the dump. This knob and the counterweight further serve as a clinker breaker to break away any clinker formation bridging the grates and dump.

The lug 31 carried by the pivot tube 30 is broken away at 35 to provide a space for receiving the respective grate bars as they are mounted on the pivot tube for replacement. In event of breakage of any of the bars in the dumping operation, they may be readily replaced on the tube when turned to dumping position, or caused to slide laterally thereon to take up the space of a broken bar which may drop off. The pivot tube has an arm 36 suitably located thereon from which an actuating dump rod extends exteriorly of the furnace walls for rocking the dump from its horizontal supporting position to its downwardly extending dumping position.

As distinguished from the usual furnace construction, and to provide a reverse flow of hot gases for drying the fuel bed and depositing partially or unburned material thereon, the usual bridge wall 37 is extended upwardly and curved rearwardly at 38 to extend over the fuel bed and thereby direct the hot gases thereover, permitting them to pass upwardly from over the fuel bed and outwardly through the passage 39 in a direction substantially as indicated by the arrows in Fig. 1. As this in effect places the secondary furnace directly above the fuel bed of the primary furnace, not only will there result an effective preheating of the oncoming wet fuel by the reverse flow of gases, but any partially burned or unburned material will drop back on to the fuel bed for consumption,

instead of being carried into the secondary furnace. This has the dual advantage of more rapid drying and preheating of the oncoming damp fuel rendering it more uniformly combustible and causes complete combustion of all material thereby eliminating the usual practice of periodically removing such material by hand or mechanical means.

For additionally serving to effect rapidity of drying of the oncoming wet fuel and increase the combustion efficiency, a series of air jets are provided for developing rapid air flow over the surface of the fuel bed for effecting removal of the moisture. As shown herein a series of jet tubes 40 are mounted in parallel spaced relation to extend through the lower portion of the bridge wall 37 through which a stream of steam driven air is directed over the lower half of the fuel bed propelled by the steam nozzle 41. An opposed companion series of air jets 42 are mounted in parallel spaced relation in the top wall 43 of the furnace which are fed by the steam nozzles 44 to project the air stream downwardly over and parallel with the upper portion of the fuel bed.

To provide a zoned air control for equalizing combustion as between the dump and grate bars on the one hand, and provide an air supply to the fuel passing over the forehearth, the ashpit 27 communicating with the dump bars is sealed off by a division wall 45. Said division wall has an opening 46 into the ashpit providing an air conduit which is controlled by a pivotally mounted damper 47 connected to the control rod 48 extending through the clean-out trough 49 and having a clean-out opening 50 for the removable closure plate 51.

The pinhole forehearth grate 13 extends over an air chamber 52 into which air is directed by the conduit 53 controlled by the damper 54. The air supply entering the furnace below the grate bars 17 and tuyères 20 is restricted to such zone, but through manipulation of the dampers 47 and 54 the air may be admitted to the restricted zone of the dump and the forehearth respectively. Such control has the effect of controlling the combustion over the dump area where the fuel is driest and the combustion would otherwise be unduly intense. Through such air control combustion may be better equalized over the entire grate surface, including the dump. The air zone directing air to the forehearth, and the control thereof, assists in the distillation of moisture from the wet fuel and permits more rapid burning thereof over the grate.

To more conveniently and effectively prevent clogging of the grate bars 17, which comprise the series of narrow stepladder slots, a plurality of steam or air headers 55 are supported by the brackets 56 underneath said grate bars and extend in parallel space relation to the grate and in transverse relation to the grate bars. Each of the headers is provided with a series of nozzles 57 arranged to direct a fluid stream in a direction substantially parallel to the fuel supporting surfaces and slots in the grate bars for blowing accumulated matter therefrom to maintain the desired effective air passage to the fuel. Said headers are mounted to oscillate upon the brackets and are each pivotally connected by an arm 58 to an oscillating rod 59 provided with a pin and slot connection at one end thereof with the oscillating lever 60. Said lever is fulcrumed at 61 on a transverse beam 62 and has a handle portion 63 projecting beyond the wall 16 of the furnace. Through movement of the handle the respective headers may be oscillated in a plane parallel to said

bars so that the fluid stream projected from the nozzles may be caused to sweep over the fuel supporting surfaces of the grate bars through such area that the several headers will jointly cover the entire grate surface.

The pusher fingers 20 are manipulated in the usual manner through their several actuating rods 64 which are connected through the arm 65 to the actuating lever 66.

An advantage of the furnace structure herein shown, and wherein the secondary furnace is above the primary furnace instead of being to the front thereof, the furnace is thereby made accessible from all four sides. Thus, a clean-out opening with a closure cap is provided at 67 in addition to the end wall clean-out openings as indicated at 68 and at 50. This is a material advantage not only in rendering the interior of the furnace more accessible for cleaning, but also for repairing the grate bars, and particularly replacing burned out and broken dump bars.

From the foregoing, it will be observed that the above described furnace has many advantages both in respect to operation, maintenance, and cleaning and in respect to the efficiency, drying and preheating in the burning of the wet fuel fed thereto.

I claim:

In a furnace for burning wet fuel having a downwardly sloping grate including grate bars having substantially horizontally extending fuel supporting surfaces mounted in spaced relation to provide a series of horizontal air emitting slots therein, the combination therewith of a series of fluid discharge nozzles mounted on the underside of said grate bars directed towards said slots, said series lying in a plane substantially parallel to and spaced below said fuel supporting surfaces and slots through which a fluid stream is discharged for blowing accumulated matter therefrom, an adjustable header mounted below said grate bars carrying said nozzles in spaced relation, and means to oscillate said header in a plane parallel to said bars so that the fluid stream projected from said nozzles may be caused to sweep over the fuel supporting surfaces of said bars in a direction from one end to the other thereof.
